SHOWER BATH APPARATUS

George E. Mears, Los Angeles, Calif.

Application January 22, 1934, Serial No. 707,676

8 Claims. (Cl. 4—154)

This invention relates to bathroom fixtures and refers particularly to a shower fixture mountable on a wall above a bathtub or the like.

The general object of the invention is to provide an attractive and inexpensive attachment which is extendable and foldable, so that it may be folded neatly out of the way, when not in use, thereby to present an article of usefulness as well as of pleasing appearance.

10 More specifically, the object of the invention is to provide such shower fixture with a panel, on which a shower head is mounted, and this head is provided with an extension tube attachable to a bathroom faucet. A further object is to provide a bracket at each end of the panel, and to hold a cross rod suspended between the two brackets. Another object is to provide hinge rods fitted to swing in these brackets and to provide these hinge rods with extension rods for the purpose of extending the position of the fixture, when in use. Another object is the provision of hooks by means of which a curtain of any preferred design or pattern may be attached to all of said rods, thereby to complete a fixture for convenient use over a bathtub or other suitable receptacle and, when not in use, capable of being folded longitudinally parallel with said panel, in an out of the way position, against the bath room wall.

These and the further objects and advantages 30 of my invention are herein fully described and illustrated in the accompanying drawings, of which:

Fig. 1 is a perspective front elevation of the foldable shower fixture of my invention, as it 35 would appear when attached to a bathroom wall.

Fig. 2 is a substantially corresponding top view of the shower fixture.

Fig. 3 is a fragmentary plan view of one end 40 of the device, with the extension rod shown in position, taken in the direction of the arrow 3, of Fig. 4.

Fig. 4 is an enlarged side elevation of the fixture, taken in the direction of the arrow 4, of Fig. 1.

Fig. 5 is a perspective view of a modified form 45 of the foldable shower fixture of my invention.

Fig. 6 is a plan view substantially in agreement with Fig. 5, showing the extension rods in folded position,

50 Fig. 7 shows the reversible extension rod connection of Figs. 5 and 6 slightly enlarged.

Fig. 8 is a corresponding plan view of the reversible extension rod connection.

Fig. 9 shows one end bracket, slightly enlarged, 55 indicating the position of the cross rod and the

hinge rod, with the curtain hooks attached thereto.

Fig. 10 is a top view of the cross rod fitted with a modified form of hinge rod.

Fig. 11 is a transverse cross sectional view of the cross rod and the bracket, taken on line 11—11 of Fig. 10.

Fig. 12 is a fragmentary perspective view of a modified end bracket, in which the cross rod and hinge rod are shown seated, and

Fig. 13 is a cross sectional view, taken on line 13—13 of Fig. 12.

The device of my invention comprises a shower fixture generally designated by the numeral 2, consisting of a panel 4, to which a pair of end 15 brackets 5 may be attached, preferably by means of screws 8. A shower head 10 is shown attached to the panel 4 by means of a clamp member 12, as shown, and it may, if so desired, be attached thereto in any position most convenient in practice, as shown particularly in Figs. 1 and 5.

The shower head 10 comprises a spray chamber 14, to which a feed tube 16 is attached, and this tube carries an extension tube 18 downwardly 25 directed to terminate in a pipe adapter 20. A flexible hose 22 is attached to this adapter and its end 24 is provided with a faucet adapter 26 which may, if so desired, be attached to a conventional water faucet, substantially as indicated in dotted outline in Fig. 1.

Each bracket 6 comprises an angularly bent plate 28, having an outwardly directed extension 30. A cross rod member 32 is attached to the brackets in any manner most suitable, preferably 35 by means of rivets 34, and the purpose of this rod is to support a curtain 36, as by means of a plurality of hook members 38, see Figs. 1, 4 and 9.

On the bracket extension 30 is mounted a 40 hinge rod 40, held in position by means of a bolt seated in an eyelet member 48 of the rod and a nut 44, to provide proper tension upon said hinge rod ends 46.

The rod 40 is shaped to receive an extension 45 tube 50 having each end section 52 equipped with a knob 54 to prevent the hook members 38 from slipping off the ends when adjustment of the extension tube 50 is being made, or when the rods 40 are folded, as shown in Figs. 2 and 6.

In Fig. 3, the bracket 6 is shown supporting an eyelet member 56, comprising a stem 58, and this stem may be of any suitable length most desirable in practice. A tube member 60 is shown attached to the stem 58, and an extension 55

tube 62 is slidably positioned on this tube to provide a light-weight, adjustable rod structure.

In Fig. 5, I have shown the fixture 2 in modified form, the outer end of one hinge rod 66 being seated to turn in a block member 68. A rod 70 is pivotally joined to the block member, substantially as indicated at 72, to provide a very inexpensive and efficient hinged structure which, when it is desired to fold the rod extensions of the fixture up against the wall, may be positioned parallel to the panel 4, as shown in Fig. 6. It is to be noted that the tube 50 also is mountable on the rod 70.

As the fixture is arranged in Fig. 1, it is most conveniently mounted at the end of a bathtub, and the tubes 50 should be extended far enough along the sides of the tub to catch the spray. The arrangement of Fig. 5, on the other hand, is most conveniently placed above the inner side of the tub, and it is readily seen that, in this arrangement, the extension rods and tubes completely enclose the center portion of the tub when the curtain is hung.

In Figs. 10 and 11, a cross rod and a hinge rod, 74 and 76 respectively, are shown held in position on the bracket extension 30 by means of a bolt 42. The hinge rod 76 is shown slidably fitted with an extension tube 80, and it is shown offset relative to the cross rod 74 in order that, when not in use, it may be folded into a position unobtrusively parallel with the rod 74.

In Figs. 12 and 13, the cross rod 32 is shown positioned within sockets 82, of a modified bracket 86, and hinge rods 84 are pivotally seated in the brackets and held in position by means of cotter pins 88, to provide a very effective and inexpensive extension rod structure for the shower fixture.

While I have described my invention in its preferred forms, I do not wish to be limited to the exact details of construction herein shown and described, but reserve the right to make such modifications as may come within the scope of the appended claims.

I claim as my invention:

1. A shower bath apparatus comprising, a panel mountable on a bath room wall, a shower head positioned on said panel, a pair of brackets on the panel, a cross rod having its ends secured to said brackets, and a pair of extension rods mounted to swing on said brackets for horizontal extension and capable of being folded parallel with said cross rod when not in use.

2. A shower bath apparatus comprising, a panel, a shower head positioned on the panel, a bracket at each end of the panel, a cross rod suspended between said brackets in parallel relation to the panel, a pair of extension rods hinged on said brackets, and a shower curtain detachably

hung on said cross rod and the said extension rods.

3. In an attachable shower bath device, a panel mountable on a bath room wall, and a curtain support comprising, a bracket on the panel, an extension member, a bolt for pivotally clamping said member on the bracket, a tube mounted on said member, and an extension tube slidable on said first named tube and terminating in a knob, the said support members being horizontally extendable on the bracket to any desired position and foldable parallel with the panel when not in use.

4. A shower bath apparatus comprising, a panel mountable on a bath room wall, a shower head positioned on said panel, a bracket at each end of the panel, a cross rod suspended between said brackets in parallel relation to the panel, a rod hinged on each bracket to swing horizontally, one of said rods terminating in a head, and an extension rod pivotally mounted on said head to swing horizontally, the said three pivoted rods being extendable to any desired position and foldable parallel with said cross rod when not in use.

5. In a shower bath apparatus, a panel, a curtain, and a curtain support, said support comprising, a fixed rod parallel with the panel, and an extension rod mounted at each end of said fixed rod to swing horizontally, said curtain having suspension members for sliding engagement with said rods.

6. In a shower bath apparatus, a panel, a curtain, and a curtain support, said support comprising, a fixed rod parallel with the panel, an extension rod mounted at each end of said fixed rod to swing horizontally, and an additional extension rod pivotally mounted on the end of one of said extension rods to swing horizontally, said curtain having suspension clips attachable to all of said rods.

7. In a shower bath apparatus, a panel, a perforated bracket fastened at each end of the panel, a bolt seated in the perforation of each bracket, a cross rod having perforated ends seated on said bolts, a telescoping rod seated on each bolt to swing horizontally, and a curtain provided with clips for sliding engagement with all of said rods.

8. In a shower bath apparatus, a panel, a bracket at each end of the panel, a tube mounted on the panel intermediate said brackets and fitted at one end for attachment to a bath tub faucet, a shower head positioned on the other end of the tube, a curtain support comprising, a fixed rod parallel with the panel between said brackets, and telescoping extension rods mounted on the brackets to swing horizontally, and a curtain having clips for attachment to said rods.

GEORGE E. MEARS.
